SNOW-REMOVING APPARATUS

Clayton B. Merry, Alderwood Manor, Wash., assignor to Clayton B. Merry Equipment, Inc., Leavenworth, Wash., a corporation of Washington

Application April 11, 1955, Serial No. 500,337

4 Claims. (Cl. 37—43)

This invention relates to snow-removing apparatus and has particular reference to a rotary snow plow attachment which is especially designed for mounting upon a tractor of the type having at the rear a power take-off and a laterally spaced pair of powered lift links arranged below and at either side of a draw bar fulcrum.

The dozer blade attachment has been relied upon primarily when utilizing a tractor for snow removal. When used for such a purpose the dozer blade has many limitations including the inability to throw snow, but nevertheless it has remained as the mainstay snow removal attachment for tractors.

The present invention therefore aims to provide an effective rotary snow plow attachment of inexpensive construction which will remove either wet or dry snow with a minimum of power consumption permitting the rotary elements of the attachment to be driven from the power take-off shaft of the fore-noted type of tractor as the latter is driven to advance the attachment into the snow to be removed. As a further object the invention aims to provide such an attachment which can be selectively raised and lowered by the lift links of the tractor. Although the present invention concerns itself with a tractor attachment, it is not intended that the scope be limited to a device driven by a tractor for the invention aims to provide an effective rotary snow plow which will clear a wide path with less power consumption than is required with those rotary snow plows of the general class which utilize augers to deliver the snow to a centrally located blower or other snow throwing unit.

With yet additional objects and advantages in view which, with the foregoing, will appear and be understood in the course of the following description and claims, the invention consists in the novel construction and in the adaptation and combination of parts hereinafter described and claimed.

In the accompanying drawings:

Figure 1 is a front perspective view of my snow plow attachment complete with the optional discharge chute.

Fig. 2 is a front elevational view of the snow plow attachment in operative position connected to a tractor shown in broken lines.

Fig. 3 is a top plan view of the attachment with part of the chain housing broken away and illustrating the drive and lift connections between the attachment and a tractor shown in broken lines; and

Fig. 4 is a vertical sectional view of my snow plow attachment taken along the line 4—4 of Fig. 3.

Referring to the drawings, and particularly to Figs. 1 and 4, it can be seen that the frame proper of my snow plow includes generally U-shaped plate members providing oppositely directed coplanar flanges 10, 11 at their upper end from which depend front and back plates 12, 13. Seated on the flanges 10, 11 is an optional discharge chute 8 having triangular side panels having an angle iron border frame 9. The plates 12, 13 are spaced

2

apart to provide the throat for a discharge manifold opening into the chute 8 and terminate respectively by a forwardly extending hood 14 and a rearwardly projecting skid 15 spaced considerably below the hood. Welded to the ends of the hood and to those portions of the ends of the back plate 13 that lie below the level of the hood are a pair of end plates 16, 17. As best shown in Fig. 4, the bottom edge of each of these end plates is desirably sloped upwardly somewhat from its rear end.

The rear portion of the space between the end plates 16, 17 is subdivided by three equally spaced baffles 18—20 which extend vertically for a distance and then curve to slope upwardly at about 45 degrees into the manifold throat between the front and back plates 12, 13 as can be seen in Fig. 2. A fourth baffle 21 slopes in like manner from the end plate 16 into the manifold throat. Each of these four baffles is welded along its rear edge to the back plate and also is welded to the front plate along the manifold throat occupying portion of its forward edge.

The baffles 18—20 separate identical fans 22—25 each of which travels in a respective orbit that passes in close proximity to the bottom edge of the back plate 13 and from thence upwardly in a direction corresponding to the upward slope of the baffles to pass partly into the manifold throat. A satisfactory fan can be constructed by securing a centrally bored square reinforcing plate 26 to the rear end of a tubular hub 27 and then radiating flat blades 28 from the hub to the corners of the reinforcing plate. These blades are given a slight lead from their rear edges toward their direction of rotation and are welded to the reinforcing plate and to the hub.

The hubs of the fans 22—25 are locked by shear pins 29 to respective ends of shafts 30—33 which extend through the back plate into a chain housing 34. A sheet metal member of adequate gage is formed with a central angle section providing the floor 35 and back 36 of the chain housing and also provides a cover flange 37 and a depending anchoring flange 38 which is welded to the back plate. The cover flange 37 is complemented by one flange of an angle rail 40 having its other flange secured to the back plate. Seated on the angle rail 40 and the cover flange 37 is a flat cover plate 41 which is bolted in position. The chain housing is completed by a pair of end plates 42.

Each of the shafts 30—33 is supported by a respective pair of ball bearing units 43, 44, one mounted on the back plate 13 and the other on the back wall 36 as best shown in Fig. 4. Bolts 49 hold each bearing unit 44 in place along with an end cap 45 in each instance excepting for the shaft 31 which extends rearwardly beyond the chain housing to make a universal connection 46 with an expandable drive shaft 47 having a universal joint 39 at its other end. Each of the bearing units 43 is held by bolts 48 to the back plate and a complementing reinforcing ring 50. Spacing washers 51 are placed between the fans and the rings 50 to protect the heads of the bolts 48.

60 To transfer power from the shaft 31 to shafts 30 and 32, a pair of sprockets 52', 52 are mounted on shaft 31 and running from these sprockets to mating sprockets 53, 54 on the shafts 30, 32, respectively, are chains 55, 56. The shaft 33 in turn receives its power from shaft 32 via a chain 57 driving between sprockets 58, 59.

Extending rearwardly from a weld connection with the upper center of the back plate 13 is an arm 60 which is provided with forks 61 at its free end. Adjacent these forks are downwardly diverging braces 62, 63 which intersect with outer channel arms 64, 65 and legs 66, 67. These outer arms slope downwardly in converging rela-

tion from the upper corners of the back plate whereas the legs 66, 67 slope upwardly from the lower corners of the back plate to make the intersections with the lower ends of the braces 62, 63. At these intersections are secured oppositely projecting trunnions 68, 69. The skid plate 15 may be braced by members 70.

Referring to Fig. 3 it is seen that I have illustrated in broken lines the rear end portion of a tractor of the type having powered lift links 71, 72 arranged below and at either side of a forked draw bar fulcrum 73. Directly below the latter is a power take-off. My snow plow attachment is operatively mounted on the tractor by fitting eyes at the outer ends of the lift links 71, 72 over the trunnions 68, 69, making a drive connection between the tractor's power take-off shaft and the universal 39 of the drive shaft 47, and interconnecting the forks 61 and the fulcrum 73 by pin connections with a draw bar 74 having suitable eyes at its ends. Locking pins 75 are provided for the outer ends of the trunnions. It will be apparent that when my snow plow is thus mounted on the tractor, the operator can raise and lower the snow plow at all by correspondingly powering the lift links 71, 72. At all times power can be selectively supplied to the fans 22-25 from the tractor via the drive shaft 47 to the fan shaft 31 and hence to the fan shafts 30, 32 and 33 through the chain and sprocket drive arrangement in the chain housing.

It should be noted that the direction of rotation of the fans and the upper sloped portions of the baffles cooperate to guide snow engaged by the blades 28 of the fans toward one side of the snow plow. Use of the chute 8 is recommended in dry snow conditions to aid this snow guiding action of the baffles and fan blades, particularly where a wind is present opposing throwing of the snow. The border frames 9 of the chute have a detachable bolt connection with the flanges 10, 11 so that the chute can be readily removed when wet snow conditions are encountered in which the snow has a tendency to pack. Such wet snow is heavy enough that the guiding influence of the chute is not necessary, and in fact, the chute may be a deterrent because the wet snow frequently will adhere to and build up in the chute. Accordingly, it is seen that use of the chute is optional depending upon the type of snow to be removed and the wind condition.

After my snow plow has been mounted on the rear of the tractor as afore-described, the tractor operator commences snow removal, after lowering the snow plow into ground adjacency, by backing the tractor while the fans 22-25 are powered from the power take-off. As the tractor is backed the rotating fans performe advance into the snow and cause the same to be thrown upwardly and outwardly well to one side of the travel path of the apparatus. The fans are purposely left exposed to the ground surface therebeneath because in wet snow conditions this keeps the snow from packing, first against the lower portions of the back plate 13, baffles 18-20 and end plates 16, 17 that lie outside of the fans' rotational orbits to form snow walls between the fans which are generally triangular when viewed from the front of the snow plow, and then as a continuous wall bridging between these triangular snow walls in front of the fans making the latter useless. To elaborate, when the fans are exposed to the ground surface any snow packing between the lower half of the rotational orbits of the fans and the baffles must rub over the ground sur-

face as it attempts to build up and the resulting friction thereon causes the packing snow to break up and lose its bond with the snow plow structure and pass into the adjacent fan. When the snow to be cleared is deeper than the height of the fans, the tractor can make short passes with the fans at varying heights with respect to the ground surface, each pass having a maximum length determined by the distance from the fans to the rear wheels of the tractor so that these wheels will not track over snow to be removed.

The advantages of the invention, it is thought, will have been clearly understood from the foregoing detailed description of the illustrated preferred embodiment. Minor changes will suggest themselves and may be resorted to without departing from the spirit of the invention, wherefore it is my intention that no limitations be implied and that the hereto annexed claims be given a scope fully commensurate with the broadest interpretation to which the employed language admits.

What I claim is:

1. In a rotary snow plow, a frame, a gang of fans journal-mounted on said frame at the front thereof in close side-by-side relation about generally horizontal parallel axes and tracking in close proximity to the bottom level of the frame, each said fan being exposed to the front and having its entire axial length exposed to the bottom, means for driving said fans in a common direction of rotation, a discharge manifold extending across the frame above said gang of fans and having a bottom throat portion of constant height partly occupied by a minor upper part of the rotational orbit of each fan, said manifold increasing in height above said throat portion from a root end at one side of the frame to a discharge mouth at the other side of the frame and the direction of rotation of said fans at the top of their rotational orbits being toward said discharge mouth, baffles carried by the frame between said fans and at the end of the gang below said root end, said baffles having their upper end portions extending into said throat portion and bending toward said discharge mouth for directing snow thereto from the fans, and means for advancing said frame frontwise.
2. The structure of claim 1 in which a hood projects forwardly from the base of said throat portion for the length of the latter and has end plates depending therefrom and extending rearwardly to the back of the frame.
3. The structure of claim 2 in which the portion of said manifold above its said throat portion is detachable from the latter.
4. The structure of claim 1 in which said baffles extend into said throat portion to a height above that of the rotational orbits of the fans.
